(57) **CLAIM**

The ornamental design for a wash carriage rack, as shown and described.

DESCRIPTION

FIG. 1 is a front, top, right, perspective view of a first embodiment of a wash carriage rack;

FIG. 2 is a rear, bottom, left, perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof;

FIG. 8 is a bottom plan view thereof;

FIG. 9 is a front, top, right, perspective view of a second embodiment of a wash carriage rack;

FIG. 10 is a rear, bottom, left perspective view thereof;

FIG. 11 is a front elevation view thereof;

FIG. 12 is a rear elevation view thereof;

FIG. 13 is a right side view thereof;

FIG. 14 is a left side view thereof;

FIG. 15 is a top plan view thereof; and,

FIG. 16 is a bottom plan view thereof.

The dash-dash broken lines shown in the drawings illustrate portions of the wash carriage rack that form no part of the claimed design. The dot-dash broken lines shown in the drawings define the bounds of the claimed design and form no part thereof.

1 Claim, 16 Drawing Sheets
